UNITED STATES PATENT OFFICE.

WILLIAM JAMES PYLE, OF OSCEOLA, NEBRASKA.

GATE.

SPECIFICATION forming part of Letters Patent No. 365,860, dated July 5, 1887.

Application filed April 26, 1887. Serial No. 236,927. (No model.)

To all whom it may concern:

Be it known that I, WILLIAM JAMES PYLE, a citizen of the United States, residing at Osceola, in the county of Polk and State of Nebraska, have invented a new and useful Improvement in Gates, of which the following is a specification.

My invention relates to an improvement in gates; and it consists in a certain novel construction and arrangement of parts for service, fully set forth hereinafter, and specifically pointed out in the appended claims.

The object of the invention is to provide a gate for farm and other use which will be lighter, stronger, more durable, and cheaper than those now in general use. I attain this object in the device illustrated in the accompanying drawings, in which—

Figure 1 is a perspective view of a fence provided with my improved gate. Fig. 2 is a detail view of the tubular brace-bar; and Fig. 3 is a detailed vertical sectional view of the wooden bar of the gate, showing the arms G and H attached thereto.

25 A represents the gate, the construction of which is as follows: A metallic tube or pipe, B, is bent downward at right angles at a suitable distance from one end, thereby forming the arm C, which constitutes the top bar of 30 the gate, and the vertical arm E. A similar tube or pipe is then bent at a suitable angle, at b, and is secured to the arm C at a suitable distance from the outer end thereof, either by welding or in any other suitable manner. The 35 extremities of the tube or pipe diverge downwardly, the front one forming the brace-arm H, and the rear one forming the brace-arm F, from which depends a vertical arm, G. The lower front end of the arm H is flattened to 40 form an eye, and is bolted to the inner side of a wooden vertical bar, D, and the front end of the arm C is screw-threaded, passed through an opening near the upper end of the bar D, and provided with a clamping-nut fitting in a 45 recess in the front side of the said bar; as shown at Fig. 3.

There is a small space between the lower end of the vertical arm E and the upper end of the vertical arm G, for a purpose to be hereinafter explained.

50 I and K represent, respectively, the front and

rear posts of the gate--or, in other words, the latch and hinge posts—and in the said hinge-post K are secured, by screwing or bolting, the eyes L and M, respectively, at the upper and 55 lower ends of the post, and the said upper eye is adapted to have the vertical arm E passed therethrough, and the said lower eye is adapted to have the vertical arm G passed therethrough.

60 N N designate the horizontal wires of the gate, of any desired number, and secured, respectively, to the standard D and the vertical arms E and G. The inclination of the brace-bars F and H is designed to be adjusted to the 65 strain which the gate is designed to bear, and, as the upper or inner ends of the said braces are formed integrally with the top bar, C, at the said point b, there is no possibility of that part of the gate giving way. The said space 70 between the lower end of the arm E and upper end of the arm G is intended to allow the passage of the eye L therethrough, and it will be seen that when the gate is properly constructed, so that the thrust of the braces F and H accurately meets the strain on the gate, the gate 75 will hang perfectly true and swing clear of the ground at all times.

The rods forming the gate are made tubular, to add to the lightness of the same without 80 detracting materially from the strength thereof, and it will be readily appreciated that the said gate may be very easily swung, is very 85 simply constructed, and may be easily set up in the desired place in a very short time. When 90 the wires N N are properly attached to the frame of the gate, it will be found capable of turning both large and small animals, the said wires being placed close together when very small animals are to be confined thereby.

Having thus described my invention, I claim—

1. A gate-frame comprising the bar B, bent at right angles to form the horizontal arm C and the vertical depending arm E, a bar bent 95 at b and attached to the arm C, and forming the downward-diverging brace-arms H and F, the latter being provided with the depending vertical arm G, and the vertical bar D, attached to the front ends of arms H and C, substantially as described.
2. A gate comprising the bar B, bent at

right angles to form the horizontal arm C and the vertical depending arm E, a bar bent at *b* and attached to the arm C, and forming the downward and diverging brace-arms H and F, 5 the latter having the depending vertical arm G, the bar D, attached to the front ends of arms H and C, and the wires N, connecting the arms E and G with the bar D, substantially as described.

10 3. A gate-frame comprising the horizontal arm C, having the vertical arm E, and the

brace-arm F, having the vertical arm G, said arms E G forming the pintles for the gate-hinge, and said brace-arm F being connected to the horizontal arm C, as set forth.

15 In testimony that I claim the foregoing as my own I have hereto affixed my signature in presence of two witnesses.

WILLIAM JAMES PYLE.
